UNITED STATES PATENT OFFICE.

ADOLF ROMINGER, OF GUTTENBERG, NEW JERSEY.

EMBROIDERY-FRAME.

1,116,740.

Specification of Letters Patent. Patented Nov. 10, 1914.

Application filed May 21, 1913. Serial No. 768,949.

To all whom it may concern:

Be it known that I, ADOLF ROMINGER, a citizen of the United States of America, residing in Guttenberg, in the county of 5 Hudson and State of New Jersey, have invented certain new and useful Improvements in Embroidery-Frames, of which the following is a specification.

This invention relates to certain improvements in the embroidery-frame for which Letters Patent were granted to me heretofore on February 28, 1911, No. 985,453, whereby the embroidery-frame can not only be used for embroidering ornaments, initial 10 letters, etc., in the corners of handkerchiefs and other articles, but also for embroidering ornamental designs on one or more sides of the articles; and for this purpose the invention consists of an embroidery-frame 15 which comprises an upper and a lower frame-piece, a plurality of parallel channel-bars attached to said frame-pieces, clamping bars covered with yielding material vulcanized on and anchored to said bars, said 20 clamping bars being detachably pivoted to the upper ends of the channel-bars, means on the lower frame-piece for engaging the clamping bars for holding them in the channel-bars, and clamping clips attached to the 25 underside of the upper frame-piece between said channel-bars flush with the face of the same.

The invention consists further in certain details of construction of the channel-bars 30 and clamping bars which will be fully described hereinafter and finally pointed out in the claims.

In the accompanying drawings, Figure 1 represents a front-elevation of my improved 35 embroidery-frame, Fig. 2 is a horizontal section on line 2—2, Fig. 1, Fig. 3 is a vertical transverse section on line 3—3, Fig. 1, Fig. 4 is a front-view of a part of the upper frame-piece of the embroidery-frame and 40 the clamping clip for the articles to be embroidered, drawn on a larger scale, Fig. 5 is a vertical transverse section on line 5—5, Fig. 4, and Fig. 6 is a horizontal section on line 6—6, Fig. 4, drawn on a still larger 45 scale.

Similar letters of reference indicate corresponding parts throughout the different figures of the drawings.

Referring to the drawings, α and α' represent 50 respectively the upper and lower frame-pieces, b the channel-bars and c the

clamping bars of an embroidery-frame for Swiss embroidering-machines in which a number of handkerchiefs or other articles are to be embroidered at the same time. The 50 embroidery-frame corresponds in length with the embroidery-machine with which it is to be used. Into recesses in the upper and lower frame-pieces α and α' are attached the vertical channel-bars b , which are made 55 U-shaped in cross-section and reinforced at their side-walls by doubling over the sheet-metal blanks from which the same are made, as shown at b^1 in Fig. 6. This strengthening of the channel-bars is necessary for the 60 reason that they are made of greater length than the channel-bars in embroidery-frames of a similar nature which were used heretofore, so that not only ornaments, monograms, initial letters, etc., can be embroidered 65 in the corners of the handkerchiefs or other articles, but also ornaments of greater length into the sides of the articles, as for this sort of work the ordinary U-shaped channel-bars would not be long and strong 70 enough for supporting the tightly stretched portions of the articles. The channel-bars b are extended above the frame-pieces at their 75 upper ends, so that their side-walls approach each other and permit the pivoting 80 of the upper ends of the clamping bars or equivalent engaging means c to the upper ends of the channel-bars, which is accomplished by means of a screw-pivot d having 85 a head d^1 at one end and a screw-nut d^2 applied to the threaded shank of the same, as 90 shown in Figs. 1 and 4. The screw-pivot connection of the clamping bars and channel-bars permits the convenient detaching of 95 the clamping bars for repairs or renewal as required. The lower ends of the clamping bars c are slightly and gradually curved forward or offset in forward direction so as to project somewhat beyond the lower portions 100 of the side-walls of the channel-bars b for permitting thereby the tight holding of the clamping bars in the channel-bars by means of retaining catches e , which are pivoted to the lower frame-piece α' , as shown in Fig. 1, and which first grip above the offset portion 105 of the clamping bars c , and then gradually tighten their grip as they are further revolved, the offset portions of the clamping bars c acting as wedges. The lower ends c^1 110 of the clamping bars c are extended below the frame-piece α' and twisted into a position at right angles to the main-portion of

the clamping bars, so that the projecting ends c^1 can be used as handles in removing the clamping bars from the channel-bars, as shown in dotted lines in Fig. 3, or replacing them into the channel-bars after the articles which are to be embroidered have been placed in position between the channel and clamping bars.

The clamping bars c are provided at the sides and inner edge with a covering f of U-shaped cross-section, made of soft rubber or other elastic material. This covering f is preferably vulcanized onto the clamping bars so that it adheres firmly thereto. The outer or front edge of the clamping bar is left uncovered, but the covering f is further secured to the clamping bars by providing holes o at suitable distances from each other in the same through which the rubber covering f is passed and anchored for securing the covering in a still more reliable and secure manner to the clamping bars. This arrangement is superior to the sleeve-shaped elastic coverings which were heretofore used, and which had the disadvantage that their front-edges projected beyond the edges of the channel-bars and exerted a brake action on the shuttles as they are passed through the embroidery-machine. This is entirely avoided by leaving the outer edge or face of the clamping bars uncovered, as shown in Fig. 6, so that no part of the same can project beyond the outer faces of the clamping bars and the edges of the channel-bars.

The corners or sides of the articles to be embroidered are held in position by clamping clips g which, instead of being arranged on the faces of the upper frame-piece, are located below the same at points between the channel-bars, as shown in Fig. 1. They consist of an angular bracket g^1 that is attached to the underside of the upper frame-piece a and provided at its lower edge with a forwardly-extending flange g^2 , which flange is located within the plane of the faces of the frame-pieces. On the flange g^2 is placed a transverse detachable key g^3 , which is held in position after the corner or side-portion of the article to be embroidered is placed in position between the flange and key, and held thereon by means of a latch g^4 , which is pivoted at its upper end to the upper portion of the angular bracket g^1 , as shown in Figs. 4 and 5, so as to securely hold the article to be embroidered in on the clip.

The articles to be embroidered are placed into the embroidery-frame in the usual manner by being stretched by means of the channel-bars and clamping bars at their sides and clips at their corners, as shown at the left-hand side of Fig. 1, or with their end-portions secured by the clips and by their side-portions between the channel-bars

and clamping bars when a longer ornament is to be embroidered, as shown at the right-hand side of Fig. 1. The practical application of the embroidery-frame is thereby considerably enlarged and not confined only to ornaments in the corners, but also capable of use for embroidering the sides of articles. Furthermore, by the stronger construction and greater length of the channel-bars and clamping bars and the vulcanizing of the elastic material to the clamping bars, these parts are stronger and more permanent and not subjected to injury or wear, as no part of the same projects beyond the plane of the faces of the frame-pieces. For this reason the clamping clips are arranged in such a manner as not to project beyond the face of the upper frame-piece, and the entire embroidery-frame thereby rendered more useful for the users of Swiss embroidery-machines known as shuttle machines.

I claim:

1. An embroidery-frame, comprising upper and lower frame-pieces, upright channel-bars attached to said frame-pieces, pivoted clamping bars pivoted to the upper ends of the channel-bars and inserted into the same, U-shaped elastic coverings extending around the sides and inner edge of the clamping bars, means for locking the lower ends of the channel-bars to the lower frame-piece, and clamping clips attached to the underside of the upper frame-piece between said channel-bars.

2. In an embroidery-frame, a clamping bar provided with a U-shaped elastic covering extending over the sides and rear-edge of the bar and anchored transversely thereto and a channel bar adapted to coact with the said sides and rear edge of said clamping bar.

3. In an embroidery-frame, a clamping bar provided with transverse holes, and a covering of soft rubber extending over the sides and inner edge of the clamping bar, anchored through the holes of the bar, and vulcanized thereto and a channel bar adapted to coact with the said sides and rear edge of said clamping bar.

4. In an embroidery frame of the kind described, the combination of a stationary channel-bar provided with doubled-over reinforcing side-walls, the extremities of said doubled-over side-walls extending substantially to the rounded base of said channel-bar, and a clamping bar pivoted to the upper end of said channel-bar, and provided with a U-shaped elastic covering extending over the sides and rear edge of the bar and anchored thereto, and means for locking the lower end of the clamping bar to the channel-bar.

5. In an embroidery frame, a U-shaped channel-bar provided with outer reinforcing walls for the side-walls, doubled over from

the front edges of the same, said outer reinforcing walls having their extremities extending substantially to the rounded base of said U-shaped channel-bar, and a clamping bar adapted to coact with said channel-bar.

6. In an embroidery-frame, the combination of upper and lower frame-pieces, upright channel-bars attached thereto, and clamping bars pivoted to said channel-bars, said clamping bars being gradually and increasingly offset forwardly at their lower ends, and movable means for locking the lower ends of the channel-bars to the lower frame-piece, said means being adapted to first engage the clamping-bars above the offset ends, and then, upon further movement, engage said offset ends.

7. An embroidery-frame, comprising upper and lower frame-pieces, upright channel-bars attached to said frame-pieces, clamping bars pivoted to the upper ends of the channel-bars and provided with a U-shaped elastic covering and offset lower ends, means for locking the offset lower ends of the channel-bars to the lower frame-piece, and clamping clips attached to the underside of the upper frame-piece between the channel-bars.

8. An embroidery-frame, comprising upper and lower frame-pieces, upright chan-

nel-bars attached to said frame-pieces, clamping clips for the articles to be emitted to the upper ends of the channel-bars and provided with a U-shaped elastic covering, means for locking the lower ends of the channel-bars to the lower frame-piece, and clamping clips for the articles to be embroidered, said clips being attached to the underside of the upper frame-piece and composed of an angular bracket having a flange at its lower end, a detachable key-piece, and a pivoted locking latch for the same.

9. An embroidery-frame, comprising upper and lower frame-pieces, upright fabric engaging means attached to one of said frame-pieces, and clamping clips for the articles to be embroidered, said clips being attached intermediate said frame-pieces, and lying intermediate the longitudinal faces of said frame-pieces, said clips being entirely within the exterior faces of the frame-pieces.

In testimony, that I claim the foregoing as my invention, I have signed my name in presence of two subscribing witnesses.

ADOLF ROMINGER.
